COMBINED GOLF BALL MARKER AND HOLDER

Janice M. Fisher, 1585 Chamber,
St. Paul, Minn. 55106

Filed Aug. 28, 1970, Ser. No. 24,756

Term of patent 14 years

Int. Cl. D21—02

U.S. Cl. D34—5

Fig. 2

Fig. 4

Fig. 3

FIG. 1 is a front view of the combined golf ball marker and holder showing the embodiment of my new design;

FIG. 2 is a side view of the combined golf ball marker and holder;

FIG. 3 is a sectional side view of the combined golf ball marker and holder without the clip portion to better show how the center disc projects forward;

FIG. 4 is a rear view of the combined golf ball marker and holder.

I claim:

The ornamental design for a combined golf ball marker and holder, as shown and described.
